Albert J. Hippman, Dolton, Ill., assignor to Production Pattern Company, Dolton, Ill., a corporation of Illinois

Application December 6, 1946, Serial No. 135,308

Term of patent 14 years

(Cl. D35—2)

To all whom it may concern:

Be it known that I, Albert J. Hippman, a citizen of the United States, residing at Dolton, in the county of Cook and State of Illinois, have invented a new, original, and ornamental Design for a Transplanting Trowel, of which the following is a specification, reference being made to the accompanying drawings, forming a part thereof.

In the drawings:

Fig. 1 is a top plan view of a transplanting trowel, showing my new design;

Fig. 2 is a bottom plan view;

Fig. 3 is a side elevational view;

Fig. 4 is a front elevational view; and

Fig. 5 is a rear elevational view.

I claim:

The ornamental design for a transplanting trowel, as shown.

ALBERT J. HIPPMAN.
